SHOE TREE

James B. Mutch, Camden, N. Y., assignor to
Schelter Last Co., Inc., Rochester, N. Y., a cor-
poration of New York

Application February 4, 1946, Serial No. 645,340

1 Claim. (Cl. 12—128.2)

1

My invention relates to shoe trees or forms and more particularly to expandible shoe trees or forms used in connection with men's or women's shoes for preserving the original shape thereof.

In using a shoe tree or form, it is important that the forepart of the tree be inserted in the shoe as far forwardly as possible and that the sides of the forepart of the tree, after the tree has reached its fully forward position, be expanded sidewardly into engagement with the inner sidewalls of the shoe in close fitting shoe shaping relation therewith. It is moreover desirable that the tree be capable of easy and quick insertion into the shoe.

An object of my invention is to provide a simply constructed shoe tree which may be more easily and quickly fitted into the shoe.

Another object of my invention is to provide a shoe tree in which the forepart is positively held in collapsed position until it is fully forward in the shoe, after which the halves of the forepart are expanded sidewardly against and into intimate contact with the inner sidewalls of the shoe during the act of positioning the heel piece of the tree in its proper position in the heel of the shoe.

My invention further contemplates the provision of a shoe tree which is longitudinally expandible and contractible and in which the two halves of the forepart are positively held collapsed so that the forepart may be fully positioned in the toe of the shoe with the parts in such collapsed condition; and as the tree is longitudinally contracted to enable insertion of the heel piece of the tree into the heel of the shoe, the two halves of the forepart are forcibly and positively expanded with the two halves of the forepart moving in parallelism into firm and form fitting relation with the inner sidewalls of the shoe.

Other objects and advantages of my invention will be set forth more particularly in the claim and will be apparent from the following description, when taken in connection with the accompanying drawings, in which:

Fig. 1 is a top plan view of the shoe tree of my invention with some of the parts of the tree being indicated in dotted lines;

Fig. 2 is a view taken substantially on the line 2—2 of Fig. 1 in the direction indicated by the arrows;

Fig. 3 is a view taken substantially on the line 3—3 of Fig. 1 in the direction indicated by the arrows;

2

Fig. 4 is a view taken substantially on the line 4—4 of Fig. 1 in the direction indicated by the arrows;

Fig. 5 is a plan view of the spreader for expanding the halves of the forepart of the tree laterally;

Fig. 6 is a plan view of the shoe tree of my invention showing a shoe partly in section and with portions of the forepart of the shoe tree cut away more clearly to illustrate the operation of the tree; and

Fig. 7 is a view taken substantially on the line 7—7 of Fig. 6 in the direction indicated by the arrows.

In the accompanying drawings, I have illustrated the preferred embodiment of the invention wherein the shoe tree comprises a forepart, generally indicated by the numeral 11. The forepart is divided longitudinally thereof as indicated at 12, preferably along approximately the longitudinal center line into two forepart sections 13 and 14. The forepart is connected by means presently described to a heel piece or heel section, generally indicated by the numeral 16.

The forepart sections 13 and 14 are laterally expandible along the plane of division 12 from the collapsed position shown in Fig. 1 to the expanded position shown in Fig. 6. This expansion and contraction of the halves of the forepart is accompanied or controlled by the forward and rearward movement of a spreader 17 as it moves from the dotted line position, shown in Fig. 1, to the solid line position shown in Fig. 6.

The forepart of the tree is shaped so that when it is in the expanded position shown in Fig. 6 it will conform to the configuration of the interior of the front portion of a shoe. The forepart, when expanded, intimately engages the inner sidewalls of the shoe for the purpose of restoring and preserving the shape thereof. Preferably the sections of the forepart are constructed of wood but other suitable materials such, for example, as plastics might be employed.

The spreader 17 (Fig. 5) is preferably constructed of fiber or other suitable non-metallic material and comprises a flat plate of pressed fibrous material which is tapered forwardly and rearwardly from a point 15 intermediate its ends. The front end of the spreader, as indicated at 18, is of decreased width and rounded. The side edges, as indicated at 19, from the point 15 of greatest width of the spreader are straight and converge toward the rounded forward end of the spreader. The rearward end of the spreader 17 is provided with a cut-out portion 21 and has a

3

pair of inwardly projecting lugs 22 for a purpose which will presently appear. The spreader is provided further with a pair of cam slots 23 which converge forwardly at an angle such that the slots are substantially parallel with the straight converging side edges 19 of the spreader.

The opposing faces of the forepart sections 13 and 14 are provided with registering or aligned substantially horizontal grooves 24 (Figs. 2, 3 and 4). The grooves 24 extend inward from the plane of separation 12 of the forepart sections. As shown in Fig. 7 the forward portion of the grooves have a slight upward tilt and the grooves are adapted to slidably receive the spreader 17.

The grooves 24 are tapered forwardly to conform to and cooperate with the taper of the side edges 19 of the spreader. Thus, when the spreader is moved forwardly from the position shown in Fig. 1 to that shown in Fig. 6, the side edges of the spreader will normally substantially continuously engage the sides or bottoms 25 of the grooves for the purpose of assisting in the shifting the halves of the forepart of the tree to their expanded position while guiding them so that they move substantially in parallelism with each other.

At the rear of the sections 13 and 14 the grooves are tapered to a lesser extent than the spreader, as indicated at 26, to provide clearance around the rearward end of the spreader. When the sections are collapsed, as shown in Fig. 1, the spreader is withdrawn rearwardly far enough to permit the sections 13 and 14 to shift so that their side edges move into the substantially common plane 12 and engage each other. In this position of the parts the forepart is of the smallest lateral dimensions possible.

The sections 13 and 14 of the forepart are preferably, at least partially, guided in their lateral movements by a floating transverse pin 27. For the purpose of receiving the pin, the sections of the forepart are provided with aligned transverse bores 28 slightly larger in diameter and combined length than the pin 27 so as to freely and loosely receive the same. While I have shown the pin as loose so that the sections may shift freely with respect thereto, it would, of course, be possible to fix the pin with respect to one forepart section and permit the other section to shift with respect to it.

Preferably the guide pin is located approximately adjacent the longitudinal center of the forepart for the purpose of more effectively guiding the movements of the sections. The guide pin is preferably of wood, but any other suitable material may be used. The pin, while it serves in general as a guide, is sufficiently loose in the openings to permit some shifting of the sections of the forepart out of parallelism with each other should such shifting be necessary to enable the tree more effectively to conform itself to the shape of the forepart of various shoes with which it may be employed.

Extending vertically and fixed in each of the sections 13 and 14 is a preferably wooden pin 29. The pins lie in substantially the same lateral plane, traverse the grooves 24 formed in the forepart sections, and lie in the cam slots 23 of the spreader. When the parts are shifted from the position shown in Fig. 1 to that shown in Fig. 6, the inner side edges of the cam slots 23 engage the pins and cause the sections to be cammed and positively spread apart. This action is assisted by the spreading action of the side

4

edges 19 of the spreader as they move forwardly in engagement with bottoms of the grooves.

As will be appreciated, the rearward ends of the slots 23 limit the spreading movement of the sections thereby enabling the length of the guide pin 27 to be determined so that it will be retained in its openings when the tree is spread to its maximum expanded condition. Thus, the floating guide pin can not be accidentally displaced.

10 A pair of aligned openings 31 is provided in the forepart sections. These openings are adapted to receive a coiled spring 32. A nail 33 is provided adjacent each end of the spring which extends through a coil of the spring for the purpose of anchoring each end of the spring to one of the sections 13 and 14. The spring is arranged so that it is tensioned slightly when the parts are in the collapsed position shown in Fig. 3. Any effort to expand or shift the sections with respect to each other must be performed against the collapsing effort of the spring 32. Thus, the sections of the forepart are normally retained in the collapsed position shown in the Fig. 1.

The fact that the forepart is normally maintained collapsed is one of the important aspects of my invention since it enables the forepart of the tree to be fitted to the shoe while the forepart is in a collapsed condition. Since the forepart is usually made considerably narrower than the width of the shoe with which it is normally to be used, this arrangement enables the forepart to be slipped into the shoe readily and quickly. The forepart may then be shifted forwardly in the shoe to its maximum forward position while the spring retains the sections collapsed.

The location of the spring 32 with respect to the spreader is of considerable importance. With the spring located, as shown in Fig. 1, the tendency is for the spring to pull the two halves of the forepart together and thereby cause the side edges 19 of the spreader to ride in the bottoms of the horizontal grooves 24, with the bottoms of the grooves pressed against the straight side edges 19 of the spreader throughout their length. When the spreader is shifted forwardly the spring tends to maintain this relationship, as will be clear from an examination of Fig. 6. That is, the spring is so located with respect to the spreader that it does not cause the forepart sections to rock upon the spreader during movement of the spreader.

The above will perhaps be more clear if the operation which would occur if the spring were located more nearly toward the toe of the forepart is considered. Thus, for example, if the spring were located well forwardly of the curved portion 18 of the spreader, upon shifting the spreader forwardly, there would be a tendency for the spring to cause the sections of the forepart to rock about the forward end of the spreader. Under such circumstances, the rear of the forepart would be spread more rapidly, particularly at the beginning of the forward movement of the spreader, than the toe portion resulting in an undesirable expanding action of the forepart sections.

The most satisfactory results are secured when the two halves of the forepart move away from each other while being maintained substantially in parallelism. While I have shown the preferred location for the spring, it is possible to locate the spring at any point between slightly forward of the position shown and a point just rearward of the guide pin 27. With the spring located within

these limits, the spring lies for the most part within the confines of the movement of the straight side edges 19 of the spreader. There is no tendency for the sections to be rocked by the spring about the spreader so as to move out of parallelism with each other. While it is desirable that the two halves of the forepart be maintained in parallelism, it will be appreciated that the two sections can be deformed out of parallelism if this action is required by reason of the necessity of the forepart conforming to the shape of the forepart of the shoe to which the tree is being fitted.

The lugs 22 are adapted to fit into openings 34 formed on the forward ends of a tubular member 36. This arrangement provides a non-rigid connection between the tubular member 36 and the spreader to enable the tubular member 36 to be pivoted about the lugs 22. The tubular member 36 is provided with a pair of aligned slots 37 which are adapted to receive a cross pin 38. The cross pin 38 is rigidly connected to the forward part of the heel piece as shown in Fig. 7. The heel piece is provided with a bore 39 adapted to receive the end of the tubular member 36. A spring 41 seated in the end of the bore, as shown at 42, has its other end pressing forwardly on the end of the tubular member 36.

The spring 41 normally retains the parts so that the tree is expanded in a longitudinal direction to its fullest extent. The spring 41 is also of considerably greater strength than the spring 32 so that when the spring 41 is compressed, while the forepart of the tree is held against forward movement, the pressure of the spring 41 pushes the spreader forwardly against the collapsing effort of the spring 32.

The heel piece 16 of the shoe tree is preferably shaped at its rear edge 43 to conform generally to the shape of the heel of the shoe so that as indicated in Fig. 7 it will engage the upper edge or upper section 44 of the heel of the shoe, exert pressure thereon, and prevent the edges 46 of the shoe from sagging. This arrangement, when the trees are regularly used with a pair of shoes, minimizes the tendency of the sides of the shoe to gape at the ankle. While the heel part of the tree may be of any suitable configuration, I have shown it formed into a handle 47 to enable convenient operation and handling of the tree.

When the tree is to be fitted to a shoe, the parts are in the transversely collapsed position of Fig. 1. In this position of the parts, the forepart of the tree may be quickly and freely inserted in the shoe and pushed forwardly to its fullest extent. The user then may pivot the heel section of the tree on the lugs 22 while simultaneously pushing forward on the handle 47 so as to decrease the over-all longitudinal length of the tree. When the over-all length of the tree has been contracted sufficiently, the heel piece may be pivoted downwardly so as to be positioned in the heel of the shoe, as shown in Fig. 7.

During the contraction of the spring 41, the force thereof is transmitted to the spreader thereby overcoming the collapsing effort of the spring 32 and causing the sections of the forepart to move in parallelism with each other into intimate shoe shaping relation with the inner 70 sidewalls of the forepart of the shoe.

It will be particularly observed that no spreading action of the forepart of the tree occurs until after the tree is in its fully forward position and until an effort is made to contract the spring 41 for the purpose of fitting the heel of the tree into the heel of the shoe. Because of the location of the spring with respect to the spreader, the engagement of the side edges of the spreader with the bottoms of the grooves and the guide pin, the sections of the forepart will move substantially in parallelism at all times unless deformed from this parallel relationship by the shape of the particular shoe with which the tree is employed.

While I have shown and described the preferred form of my invention, it will be appreciated that various changes and modifications may be made, particularly in the form and relation of parts, without departing from the spirit of my invention as set forth in the appended claim.

I claim:

A shoe tree comprising, in combination, a forepart divided longitudinally into two sections movable transversely with respect to each other from a collapsed position to an expanded position, a spring extending between the sections adjacent the longitudinal center thereof for normally drawing the sections into collapsed position, a guide extending between the sections and located adjacent the longitudinal center of the forepart but rearward of the spring, a groove in each of said sections, a spreader having diverging spreader edges extending into and engaging the side walls of said grooves, parts of the engaging portions of said spreader with the side walls of said grooves being substantially throughout movement of the spreader from a rearward position to a forward position in which the sections are spread in the same transverse plane as the spring to force the sections to move transversely with respect to each other in parallelism unless such action is modified by engagement with the inner walls of the shoe, an element pivotally connected to said spreader independently of said guide, a heel piece having a bore into which said element extends and a spring in said bore normally urging said element in a direction such as to move the heel piece and the spreader apart.
